UNITED STATES PATENT OFFICE.

JOHN L. SCHINDLER, OF FRIEND, OREGON.

THROTTLING DEVICE FOR HYDROCARBON-ENGINES.

1,089,275.

Specification of Letters Patent. Patented Mar. 3, 1914.

Application filed May 15, 1913. Serial No. 767,817.

To all whom it may concern:

Be it known that I, JOHN L. SCHINDLER, a citizen of the United States, residing at Friend, in the county of Wasco and State 5 of Oregon, have invented certain new and useful Improvements in Throttling Devices for Hydrocarbon-Engines, of which the following is a specification.

Under certain conditions of service at the 10 present time, it is desirable that motor propelled vehicles be subject to definite control with respect to speed whereby when the vehicle or its motor reaches a predetermined maximum speed any excess will be automatically cut off. Thus the operator of a 15 motor vehicle may be forcibly required to keep within specified limits of speed by the provision of means for cutting off the volume of charge of gas admitted to the engine 20 when such limit is passed and to this end my invention relates to that class of charge controlling devices adapted to be employed in conjunction with hydrocarbon engines, being preferably interposed between the 25 carburetor and the engine in the intake manifold.

My invention contemplates the provision 30 of a governor operable by the suction of the charge through the manifold to automatically operate a throttle valve, when the pressure of the suction through the manifold reaches a predetermined point, manually operable means coöperating with the 35 governor aforesaid whereby the sensitiveness of its action may readily be controlled according to the predetermined limit of speed desired.

With these and other objects in view, my invention consists of certain combinations, 40 constructions, and arrangements of parts all as hereinafter more fully described, claimed and illustrated in the accompanying drawings, wherein:

Figure 1 is a view in elevation showing 45 the application of my throttling device to a hydrocarbon engine. Fig. 2 is a longitudinal sectional view through the device alone. Fig. 3 is a transverse sectional view on the line 3-3 of Fig. 2. Fig. 4 is a

transverse sectional view on the line 4-4 of 50 Fig. 2. Fig. 5 is a view in elevation partly broken away and showing a slightly modified form of construction of the shell casing for my device.

Throughout the following detail description, and on the several figures of the drawings, similar parts are referred to by like reference characters.

Specifically describing the preferred embodiment of my device, and referring to the 60 drawing, the numeral 1 designates a shell or casing which for purposes of convenient access to the interior is preferably composed of two sections having threaded connection as indicated at 2. As shown in the drawing 65 the ends of the casing 1 taper, though it will be understood that I need not be limited to the exact shape or configuration of this particular feature of the device.

Mounted within the casing 1 and at one end 70 of the same, on a longitudinally extending shaft 3, is a fan 4 constituting a governor as will be more apparent as this description proceeds, the fan being fixedly secured to the shaft 3 which has its bearing in a suitable 75 transverse bar 5 adjacent one end of the casing, the other end of said shaft being similarly mounted for rotation in the bearing 6 at the opposite end portion of the shell. The bearing member 6 just mentioned 80 is suitably formed to constitute a partial closure of the passage through the casing 1 and fixedly mounted upon the shaft 3 directly adjacent this bearing 6, and preferably at the outer side of the same, is a shutter 85 7 adapted when partially rotated to more or less close the passage through the casing in its coöperation with the bearing 6 aforesaid. Speaking more specifically, it will be understood that approximately a quarter 90 turn of the shutter or valve 7 will be sufficient to entirely close this passage when complete throttling of the charge being drawn through the same is effected.

Extending transversely through the casing or shell 1 is an operating rod 8 terminating exterior to the casing in a crank handle 9 for manipulation of the rod, said rod

having secured thereto within the casing a worm 10 with which meshes a pinion 11 loosely mounted upon the shaft 3 adjacent the bearing bar 5. To this pinion 11 is 5 fastened one end of a spiral spring 12 which surrounds the shaft 3 and is in turn secured at its other end to said shaft, whereby upon turning the rod 8 tension will be placed upon the shaft and the parts fixed 10 thereto, the tendency being to hold the shutter or valve in its normally open position permitting passage of the fuel or charge through the casing. It will be noted by reference to Fig. 3 that the bearing is 15 preferably formed with opposing projections or stops 13 which are adapted to limit the rotative movement of the valve both in its open and closed positions.

Describing the operation of the invention 20 and illustrating its adaptation, it is to be understood that the casing 1 with its contents is to be disposed in the intake manifold 14 of a hydrocarbon engine 15 adjacent the carbureter 16. It will be further obvious 25 that the intake manifold itself may be employed to constitute the casing for holding the governor 4, the valve 7 and other co-operating parts it being my idea, however, to employ a casing such as herein described 30 in order that the device may be applied to engines not initially furnished with the throttle control. As the mixture is drawn by the engine from the carbureter through the intake manifold 14 it passes through the 35 casing 1 and the opening 17 at the valve end of the same. When the suction created by the speed at which the engine is operated reaches a pressure which is sufficient to overcome the tension of the spring 12 on 40 the shaft 3 the governor will be operated, because of its fan-like formation, or tend to revolve and in its revolution it carries the valve 7 around so as to reduce the operative area of the openings 17 in the passage. 45 When the pressure becomes sufficient to entirely overcome the tension of the spring the valve 7 will move to a position against the stops 13 thereby entirely throttling the engine and forcibly reducing the speed until 50 the suction in the pipe reduces and allows the shutter to again open the passage through the manifold. The turning or manipulation of the operating rod 8 controls the amount of tension placed upon the shaft and 55 necessarily the time at which the pressure commences to operate the fan and its co-operating valve 7. In this manner it will be obvious that the device may be set to throttle the speed of the engine at predetermined limits.

With the foregoing in view, supposing that the owner of a motor vehicle desired that the operator should not exceed a certain limit

of speed it would only be necessary to manipulate the operating rod 8 and thereby place a predetermined amount of tension upon the shaft 3 through the medium of the spring 12. If subsequently the operator exceeded the speed limit his engine would be automatically throttled thereby effecting an 70 advantageous as well as forcible control of speed. Another advantage will be apparent in that "racing" of the engine would be eliminated by the use of this device beyond a certain speed. 75

The simplicity of the throttling device is another advantage as it may be very cheaply manufactured and installed upon any hydrocarbon engine in co-operation with its intake manifold. To facilitate the installation in the manifolds of certain engines, it may be desirable to slightly modify the construction of the casing used in my device, in the manner illustrated most clearly in Fig. 5, wherein the casing consists of three sections, the central one being designated 1^a and the end sections 2^a and 2^b having threaded connection with the section 1^a. The end sections 2^a and 2^b are externally threaded for connecting the same with the intake 90 manifold of the engine as will be obvious. 85

Having thus described the invention, what I claim as new is:

1. In throttling devices for hydrocarbon engines, the combination of a casing, a longitudinal shaft mounted in said casing, a throttling valve fixedly secured to one end of the shaft, a governor fixedly secured to the shaft at its other end in spaced relation to the valve and adapted to be operated by suction through the casing whereby the valve may be moved to regulate the operative area of the opening through said passage, a manually operable rod extending transversely through the casing, and a spring mounted upon the shaft intermediate the valve and governor and operably connected with the manually operable rod whereby to place said spring under predetermined tension normally preventing action of the governor and valve until a predetermined pressure of suction through said passage is reached. 95

2. In throttling devices for hydrocarbon engines, the combination of a casing, a longitudinal shaft mounted in said casing, a frame removably inserted in the casing and comprising spaced bearings for said shaft, one of said bearings constituting a partial closure for the passage through the casing, a fan governor fixedly mounted at one end of said shaft, and a throttle valve fixedly secured to the other end of the shaft, said valve being adapted to co-operate with the bearing closure aforesaid to regulate the 110 operative area of the opening through the 115 120 125

casing, a spring surrounding the shaft between the fan and the valve and connected to said shaft at one end, a pinion loosely mounted upon said shaft and connected with said spring at the other end, and a manipulating rod extending transversely of the casing and having a worm thereon to engage the pinion aforesaid whereby to place the

spring under tension upon rotation of the manipulating rod. 10

In testimony whereof I affix my signature in presence of two witnesses.

JOHN L. SCHINDLER.
